7 Claims

ABSTRACT OF THE DISCLOSURE

A readily adjustable and replaceable shoulder strap, consisting only of a strip of material having an abutment at one end, in combination with a brassiere, or the like, formed with eyelets at the front and back presenting apertures passing entirely therethrough. The free end of said strap is first inserted through the back eyelet and pulled entirely through until stopped by engagement of said abutment, next passed over the shoulder of a wearer and through the front eyelet, and finally pulled tight, looped and knotted to adjust the strap length.

This invention relates to improvements in garments for feminine wear, and more particularly to a garment of the brassiere type, having readily detachable and adjustable and replaceable shoulder straps.

It has been suggested that brassieres may well be provided with adjustable and replaceable straps. However, the known means for accomplishing adjustment and replacement are usually such as to present certain disadvantages. Such known means include buckles, clamps, or hooks, and the like, which are difficult to use and adjust, which fray and wear through the fabric of the straps, or the brassiere, requiring discarding of the garment, and which frequently slip, or unhook during use.

It is a primary object of the present invention to provide a garment with shoulder straps which will obviate the above-stated disadvantages.

It is another important object of the invention to provide a garment in which the strap may be replaced easily when broken, or for washing when soiled, by another strap of the same, or a different color as when needed to match the color of an outer garment.

It is a further important object of the invention to provide a replaceable shoulder strap consisting merely of a length of material with an abutment at one end, the strap being passed through apertures in opposed portions of the garment, the abutment preventing complete passage at one end of the strap, and the other end of the strap being passed through an aperture looped and knotted with a slip knot, such as a bow, which permits the ready adjustment and readjustment of the length of the strap.

Yet another object of the invention is to provide an improved detachable shoulder strap, having the above described characteristics, which may be easily inserted, adjusted and readjusted even by persons having arthritic, or other, defects which limit their dexterity.

Yet a further object of the invention is to provide an improved garment, having the above described characteristics, in which the shoulder straps may be positioned on the garment in any one of a number of selected positions to thereby best conform the garment to the individual wearer.

A still further object of the invention is to provide an improved garment, having the above described characteristics, in which the shoulder strap is free of all encumbrances and consists merely of a strip of material with a knot, or other form of abutment at one end,

2

and which may take a decorative form, such as a gathered, puckered, or pleated rosette.

It is still another object of the invention to provide a garment with shoulder straps which is of extremely simple construction, inexpensive to make, and having straps quickly and easily adjustable and/or replaceable while being worn.

The novel features that are considered characteristic of the invention are set forth with particularity in the appended claims. The invention, itself, however, both as to its organization and its method of operation, together with additional objects and advantages thereof, will best be understood from the following description of specific embodiments when read in connection with the accompanying drawing, wherein like reference characters indicate like parts throughout the several figures and in which:

FIG. 1 is a perspective view of a brassiere embodying the invention in position on the body of a wearer and as viewed from the front;

FIG. 2 is a similar perspective view of the same brassiere, but as viewed from the back of the wearer;

FIG. 3 is an exploded elevational view showing only one of the shoulder straps separated from the body portion of the brassiere;

FIG. 4 is a fragmentary elevational view showing the front end of a shoulder strap passed through a front eyelet in the brassiere and in process of being tied to adjust the length of the shoulder strap;

FIG. 5 is a view similar to FIG. 4, but showing the knot completed and the knot end tucked inside the brassiere;

FIG. 6 is a fragmentary elevational view showing another embodiment of the invention in which a plurality of laterally and vertically spaced eyelets are mounted for selective reception of an end of the shoulder strap; and

FIG. 7 is a fragmentary elevational view similar to FIG. 6, showing still another embodiment of the brassiere.

Referring now more particularly to the drawing, FIGS. 1-5 illustrate a preferred embodiment of the invention in the form of a brassiere 10 having separate, removable, adjustable, and replaceable straps 12. The brassiere may comprise any conventional construction and, as illustrated, usually is formed with the front section 14 having a pair of breast cups 16 and two side sections 18 extending rearwardly around the torso of the wearer, the ends 20 of the side sections being provided with clasp means such as hooks, not shown. At the upper edges of the front sections and centrally above each breast cup is provided an eyelet 22, desirably in the form of a metal ring having projecting teeth at the back which pierce the fabric of the brassiere and are bent to tightly clamp the eyelet in place. A triangularly-shaped reinforcing tab 24 may be stitched, or otherwise secured to the inside surface of the brassiere for more securely holding the eyelet and for strengthening the fabric surrounding each eyelet. Each eyelet, when clamped in place, leaves an aperture 26 completely through the fabric of the brassiere which, as will later be explained, enables fastening of the front end of a shoulder strap to the front of the brassiere.

Instead of a metal eyelet it is obviously possible to use eyelets of other materials, or alternatively, to form an aperture in the brassiere fabric and reinforce the edges thereof by stitching, or the like, thus avoiding the use of added metal, or plastic, parts.

Another pair of similar eyelets 22 are provided at the upper edges of the side sections, preferably near the closure ends 20 thereof, and these are intended to receive the rear ends of the shoulder straps.

The pair of separate straps 12 may be formed of plain bias tape, strips of ribbon material, or strips of any other suitable, flexible material, and may match the brassiere in color, or may match an outer garment and contrast in color with the brassiere material. Each strap is of suitable length, about 15-18 inches, to extend across the shoulder of the wearer and leave sufficient material at the ends for connection to the brassiere proper. Each strap is entirely free of clips, clasps, hooks, or other impedimentia, and consists wholly of a length of ribbon having an abutment 28 at one end intended to engage one of the rear eyelets and prevent the strap from pulling through. Desirably, the abutment, as illustrated, comprises a decorative rosette formed of gathers, or pleats of material secured at its center to the end edge of the strap, and need be of a size only slightly larger than the aperture 26 in the eyelet. Obviously, other forms of an abutment may be used as, for example, a button, a knot in the strap, a ring, a disc, or the like.

To assemble the straps with the brassiere, it is merely necessary to pass the front end 30 of each strap through one of the rear eyelets 22 and pull the strap entirely through the eyelet aperture 26 until the rosette 28 engages the eyelet and the rear surface of the brassiere side section. This is most easily done before the brassiere proper is placed around the torso of the wearer.

For persons already wearing the brassiere and wishing to replace a strap, particularly if they are obese, or otherwise lack dexterity due to physical handicap, the rear clasp ends 20 of the brassiere may be partially, or completely unhooked to loosen the garment and with the front ends of the straps unconnected, the brassiere may be rotated around the body to place the ends of the side sections in front of the wearer, whereupon the old straps may be easily removed by pulling on the rosette, and new straps inserted through the rear eyelets now positioned at the front of the body. The brassiere may then be turned back around the body to return the clasp portions 20 to the rear and re-clasped to tighten the brassiere on the body.

To fasten the front ends of the straps to the front section 14 of the brassiere and to adjust the strap lengths and the fit of the brassiere to the wearer, each front end 30, FIG. 4, is passed completely through a front eyelet 22 and extended upwardly and generally parallel, as at 32, to the strap portion covering the shoulder, then looped about said portion, as at 34, and a bow 36 formed in end 30 is passed between the strap parts 12 and 32 so as to form a slip, or half-bow knot. The loop, or bow 36 may then be pulled laterally to tighten the knot, as shown in FIG. 5, and the end of the strap 30 is tucked under the brassiere front. Since the bow knot may be formed at any position on the strap before tightening, the wearer needs merely to adjust the length of the strap passed through the eyelet to the proper position for comfort before forming and tightening the knot to arrive at the appropriate adjustment of the length of the strap. Obviously, if, during wear, the strap is too tight, or too loose, the knot may be loosened and readjusted very quickly.

In removing the straps, it is first necessary to grasp and pull the ends 30 to release the knots. Both straps can then be pulled out of the front eyelets and lifted off the shoulders. The brassiere may then be unclasped at the back and removed from the body of the wearer, or may be merely loosened and rotated around the body to place the rear in front, as explained above. The rosettes 28 may then be pulled to remove the straps through the rear eyelets.

Of course, other forms of knots may be tied in the front ends of the straps to fasten the straps and adjust the garment to the wearer. Preferably, some form of slip knot, which is as quickly and easily knotted and unknotted as that illustrated in FIGS. 4 and 5, should be used.

In FIG. 6 is shown an example of a modified brassiere in which the upper front section above each breast cup

is provided with a plurality rather than a single eyelet, and these are arranged to be both laterally and vertically spaced. In connecting the front end of the strap to the front section of the brassiere, any one of the four eyelets shown in FIG. 6 may be selected to pass the strap through and tie the strap, as explained above. This enables selection of an eyelet positioned to one side, or the other, of the center, or an upper or a lower spaced eyelet, so as to provide optimum adjustment to the comfort of the wearer.

It should be noted that with a number of eyelets grouped as in FIG. 6, the strap may be passed outwardly through one, and inwardly through another and thus, continued through as many eyelets as desired. This will avoid the need for knotting the strap as the convolutions of the strap through a number of eyelets will serve as an adequate fastening. The provision of a group of eyelets spaced as shown in FIG. 6 may be made at the rear of the brassiere, as well as at the front.

FIG. 7 illustrates another modification in which a group of three eyelets 22 and a reinforcing tab 24 are provided at the front, or if desired, at the rear of the brassiere, the eyelets being secured to the brassiere in a horizontal line and being spaced laterally apart. This provides for lateral position adjustment of the strap relying on the longitudinal position of the knot in the strap for vertical adjustment thereof.

It should be clear from the above description that the improved brassiere provides many advantages. The straps are unencumbered by clips, clasps, hooks, or similar devices, which in conventional brassieres are uncomfortable, difficult to adjust, and exert pressure against the fabric of the straps or the brassiere which tends to wear through these fabrics. The straps may be easily and quickly adjusted, or readjusted, and removed, or replaced, when torn, or soiled, to allow washing the straps separately even though the brassiere is being worn at the time of removal of the straps. An adjustment to lift and tighten, or lower and loosen the over-all fit of the garment for comfort and appearance may be made in the matter of a second or two by merely unslipping the knot and re-tightening it in a new position.

While the invention has been described as embodied in a brassiere, it should be obvious that any undergarment employing straps, such as slips, pajamas, or the like, may be provided with replaceable and adjustable straps, as described herein.

Although certain specific embodiments of the invention have been shown and described, it is obvious that many modifications thereof are possible. The invention, therefore, is not to be restricted except insofar as is necessitated by the prior art and by the spirit of the appended claims.

What is claimed is:

1. A garment comprising a front section and rearwardly extending side sections, front and rear eyelets secured to said front and side sections respectively and presenting apertures passing entirely therethrough, and a shoulder strap having an abutment larger than said rear eyelet at one end only, the free end of said strap being first inserted through said rear eyelet and pulled entirely therethrough to engage said abutment, then passed over the shoulder of a wearer and through said front eyelet, and finally pulled taut, looped and releasably knotted to comfortably adjust the strap length and the garment position on a wearer.

2. A garment according to claim 1, wherein said strap consists only of a strip of material and said abutment, said abutment comprising a decorative rosette formed of gathered material.

3. A garment according to claim 1, wherein said garment front and side sections comprise a brassiere, said eyelets being secured near the upper edges of said sections.

4. A garment according to claim 3, wherein said front section includes a pair of breast cups, there being a

pair of eyelets in said front section one secured thereto centrally above each of said cups.

5. A garment according to claim 3, wherein a plurality of eyelets spaced laterally apart are provided in at least one of said sections for selective passage of said shoulder strap.

6. A garment according to claim 3, wherein a plurality of eyelets spaced vertically apart are provided in at least one of said sections for selective passage of said shoulder strap.

7. A garment according to claim 3, wherein said sections are each reinforced in the area of securement of said eyelets by a covering layer of material, said eyelets

presenting apertures passing through the section and the reinforcing layer of material.
